UNITED STATES PATENT OFFICE.

CATHERINE O'HARA, OF NEW YORK, N. Y., ASSIGNOR TO THE BUTTERICK PUBLISHING COMPANY, (LIMITED,) OF SAME PLACE.

DESIGN FOR A CHILD'S COSTUME.

SPECIFICATION forming part of Design No. 14,499, dated December 18, 1883.

Application filed October 27, 1883. Term of patent 3½ years.

To all whom it may concern:

Be it known that I, CATHERINE O'HARA, of the city, county, and State of New York, have invented and produced a new and original Design for a Pattern of a Child's Costume, (numbered 8,922;) and I do hereby declare that the engraved prints accompanying this specification convey to any one accustomed to using paper patterns a clear understanding of how a garment made up by the pattern will appear.

The design shows a side-plaited skirt that displays a double box-plait at the front extending to the neck, under fronts extending from beneath the plait, deep jacket-fronts

curving away from the tops of the shoulders, 15 a half-fitting back, and a folded sash extending across the front under the jacket-fronts and knotted over the lower end of the center seam of the back, coat-sleeves being added.

What I claim as my invention, and desire to 20 secure by Letters Patent, is—

The design for a child's costume, as shown in the engraved prints accompanying this specification.

CATHERINE O'HARA.
